US00D995767S

(12) **United States Design Patent** (10) **Patent No.:** **US D995,767 S**
(45) **Date of Patent:** **** Aug. 15, 2023**

(54) **UNIT DOSE CONTAINER**

- (71) Applicant: **ULTRADENT PRODUCTS, INC.**,
South Jordan, UT (US)
- (72) Inventors: **John Paul Goates**, Millcreek, UT (US);
Colby M. Radmall, Pleasant Grove,
UT (US); **Bruce S. McLean**, Sandy,
UT (US); **Wade J. Cannon**, Orem, UT
(US); **Weston S. Thompson**, South
Jordan, UT (US)
- (73) Assignee: **ULTRADENT PRODUCTS, INC.**,
South Jordan, UT (US)
- (**) Term: **15 Years**
- (21) Appl. No.: **29/811,369**
- (22) Filed: **Oct. 13, 2021**

Related U.S. Application Data

- (63) Continuation of application No. 29/652,180, filed on
Jun. 4, 2020, now Pat. No. Des. 936,218.

(57) **CLAIM**

The ornamental design for a unit dose container, as shown and described.

DESCRIPTION

FIG. 1 is a perspective view of a unit dose container;
FIG. 2 is another perspective view of the unit dose container
shown in FIG. 1;
FIG. 3 is a top view of the unit dose container shown in FIG.
1;
FIG. 4 is a bottom view of the unit dose container shown in
FIG. 1;
FIG. 5 is a left-side view of the unit dose container shown
in FIG. 1;
FIG. 6 is a right-side view of the unit dose container shown
in FIG. 1;
FIG. 7 is a front view of the unit dose container shown
in FIG. 1; and,
FIG. 8 is a rear view of the unit dose container shown in FIG.
1.
The broken lines shown in the figures form no part of the
claimed design.

1 Claim, 5 Drawing Sheets
